UNITED STATES PATENT OFFICE

2,131,630

DOOR STOP

Ignatius Kreitler, River Aux Vases, Mo.

Application August 9, 1937, Serial No. 158,179

4 Claims. (Cl. 292—164)

This invention relates to door stops, and its general object is to provide a device of that character for disposal in the path of a swinging door to hold the latter in open position and which is actuated automatically for that purpose, merely by the engagement of the door therewith.

A further object is to provide a door stop that is automatic to the extent above set forth, and which must be manually actuated to release the door therefrom, merely by slight pressure on the part of the user, yet accidental releasing or closing of the door, such as by air currents, wind or the like is impossible.

Another object is to provide a door stop that is adapted to be permanently fixed in position for use, is simple in construction, inexpensive to manufacture, easy to install, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a view illustrating my door stop in use.

Figure 2 is a side elevation of the door stop per se.

Figure 3 is a top plan view thereof.

Figure 4 is a vertical sectional view, with parts in elevation.

Figure 5 is a sectional view taken approximately on line 5—5 of Figure 4, looking in the direction of the arrows.

Referring to the drawing in detail, and particularly to Figure 1, it will be noted that my door stop is adapted to be set into the floor in the path of a swinging door, and for that purpose it is provided with a substantially U-shaped frame having secured to the upper ends of the parallel arms thereof an attaching plate 2 which extends outwardly beyond the arms and has openings adjacent its outer ends to receive screws or like securing means for securing the frame within the floor and of course with the plate countersunk therein, as clearly shown in Figure 1.

Fixed to the lower or bight portion of the frame, as well as to the attaching plate 2 for disposal in close proximity to the arms of the frame are tubes 3 and 4 respectively which are

disposed parallel to each other, as well as to the arms, as clearly shown in Figures 2 and 4. The tubes are each provided with a slot 5 extending longitudinally for a portion of the height thereof from their lower ends and in their confronting faces, for a purpose which will be presently described, and while the tube 3 terminates flush with the plate 2 and is mounted in an opening therein, the tube 4 extends through an opening in the plate, and terminates a considerable distance above the plate, as best shown in Figure 4.

Mounted for slideable movement in the tube 3 is a bolt 6, and the tube 4 has slidably mounted therein a rod 7. The bolt 6 and rod 7 each have a rack 8 secured thereto and which extends through the slot, with the teeth thereof engaged with the teeth of a pinion 9 that is rotatably mounted on a stub shaft 10, and held accordingly by a nut threaded on the shaft, the latter being fixed to an upright strip 11 that bridges the bight 15 portion of the frame and the plate and has its ends secured thereto, as clearly shown in Figure 2.

The rod is recessed at its upper end to provide a hook 12 for the purpose of receiving the hooked lower end 13 of a trigger dog 14 which is pivotally mounted on a pin 15 that bridges the tube 4 adjacent the upper end thereof. The upper end of the dog 14 is reduced and secured to and extending through the reduced portion is a headed pin 16 that also extends through a slot 17 in the upper end portion of the tube 4, for disposal in the path of the door to be engaged by the latter for moving the hooked lower end 13 of the dog or catch 14 from the hook 12 of the rod 8, and against the action of a coil spring 18 that has its end convolutions engaged with the reduced upper end of the dog and the tube 4 respectively as clearly shown in Figure 4, which likewise discloses the fact that the coil spring is held in position, due to the fact that a portion thereof surrounds the headed pin.

Surrounding the shaft 10 in coiled formation and having one end fixed thereto is a spring 19 which has its opposite end fixed to the pinion 9 adjacent the periphery thereof, by a pin as shown 45 and by that structure it will be obvious that the bolt 6 is urged outwardly of its tube 3 or in projected position as shown in Figure 4. However, it will be further obvious that the bolt is held within its tube by the engagement of the hooked 50 lower end 13 with the hook 12, as shown in full lines in Figure 4. When the parts are arranged in the latter mentioned position, and the door is moved to open position, to contact the head of the pin 16, the rod will be released from the dog, 55

and the spring 19 will move the bolt and rod to the full line position of Figure 4, and thereby the bolt will be arranged in the path of the door, with the latter between the projecting upper end of the tube 4 and the bolt, as clearly shown in Figure 1.

I preferably provide a closure cap 20 for the projecting upper end of the tube 3, and which is slidably mounted thereon and secured thereto in any manner, and the cap is provided with a slot to accommodate the headed pin 16. However, any suitable means may be employed for closing the upper end of the tube 4.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A door stop comprising means to be fixed in the path of a door, a slidably mounted spring 25 pressed bolt associated with the fixed means and for disposal into and out of said path, means slidably mounted and connected to said bolt for movement therewith in unison, releasable means normally holding the slidably mounted means 30 against movement and the bolt out of said path, means included in the holding means to be engaged by said door for releasing the slidably mounted means for disposing the bolt in said path for cooperation with the fixed means for holding the door between the bolt and the fixed means.

2. A door stop comprising a frame, means fixed to said frame and to be arranged in the path of a door, a bolt slidably mounted in the frame for disposal into and out of said path, a rod slidably mounted in said frame, rack and pinion means connecting said bolt and rod for movement in unison, means releasably connected to the rod for normally holding the bolt out of said path, spring

means for urging the bolt in said path, means included in the holding means and to be engaged by said door for releasing the rod for disposing the bolt in said path for cooperation with the fixed means for holding the door between the bolt and the fixed means.

3. A door stop comprising a frame, a pair of tubes secured in said frame and one tube extending above the frame for the upper end thereof to be disposed in the path of a door, a bolt slidably mounted in the other tube for disposal into and out of said path, means slidably mounted in the extended tube, racks on the slidably mounted means and bolt respectively, a pinion meshing with the racks, spring means for the pinion for urging the bolt into said path, means releasably connected to the slidably mounted means for holding the bolt out of said path, and means for actuating the holding means and mounted on the upper end of the extended tube to be engaged by said door for releasing the holding means for disposing the bolt in said path for cooperation with the extended portion for holding the door between the bolt and extended portion.

4. A door stop comprising a frame adapted to be set into a floor, a pair of tubes mounted in the frame and one of said tubes extending above the frame for disposal in the path of a door, a bolt slidably mounted in the other tube, a rod slidably mounted in the extended tube and having a hooked upper end, racks secured to the bolt and rod, a pinion meshing with the racks, spring means for the pinion for urging the bolt into said path, a spring pressed dog pivotally mounted in the extending portion of the extended tube and engageable with the hooked upper end for holding the bolt out of said path, a headed pin engaged by the door to be actuated thereby for releasing the dog from the rod for disposing the bolt in said path for cooperation with the extended portion for holding the door between the latter and the bolt, and a cap for closing the extended portion.

IGNATTIUS KREITLER.
